(57) **CLAIM**

The ornamental design for a table and bench unit, as shown and described.

DESCRIPTION

FIG. 1 is a perspective view of the table and bench unit according to the invention;

FIG. 2 is a top plan view of the table and bench unit as shown in FIG. 1;

FIG. 3 is a side elevational view of the table and bench unit as shown in FIG. 1, the left and right sides of the design being identical; and,

FIG. 4 is an end view of the table and bench unit as shown in FIG. 1, the front and rear ends of the design being identical.
